STEROID KETO HYDROXY ACIDS AND
THEIR POLYBASIC ACID ESTERS AND
METHOD OF PREPARING SAMEErwin Schwenk, Montclair, N. J., assignor to
Schering Corporation, Bloomfield, N. J., a corporation of New JerseyNo Drawing. Application September 26, 1942,
Serial No. 459,828

15 Claims. (Cl. 260—397.1)

1

The present invention relates to the manufacture of keto hydroxy acids of the steroid series, and of their partial polybasic organic acid esters, and more particularly to the production of 3-hydroxy-12-keto-*etio* cholanic acid and its homologues, and the said esters of such acids.

It is known to prepare 3-hydroxy 12-keto cholanic acid by the oxidation of desoxycholic acid. The method consists in dissolving desoxycholic acid in glacial acetic acid whereby the 3-hydroxy group is acetylated, after which the addition of a chromic acid solution at low temperature will oxidize the remaining free hydroxy group in 12-position. However, the yields in this procedure are variable and not more than about 50% of the theory. This is apparently due to the fact that the acetylation of the acid is only partial, which causes the formation of a mixture of products from which the isolation of the desired 3-hydroxy 12-keto acid is difficult and only possible with low yields, especially if carried out with larger amounts of material. This method gives even less favorable results when used for the preparation of the lower homologues of desoxycholic acid, with a shorter side chain, corresponding to the general formula:

It is the general object of the present invention to provide an improved process for the manufacture of acids of the type represented by the above formula and also of the corresponding 3-hydroxy-12-keto cholanic acid.

I have found that improved yields of the above acids can be obtained if, prior to the oxidation, desoxycholic acid or its lower homologues or degradation products are first converted into the partial ester of a polybasic organic acid and especially of a dicarboxylic acid like phthalic or succinic acid as by reaction with the anhydride

2

of such acid. This reaction is practically quantitative and involves only a relatively simple procedure. The so obtained partial or half esters of the polycarboxylic acids are then oxidized in any suitable manner as by means of chromic acid, and the reaction products, the partial or half esters of the 3-hydroxy-12-keto-acids, may then be isolated by precipitation on ice, sodium bisulfite being suitably employed to decompose excess oxidizing agents. These partial or half esters may be used as such, or may be dissolved in an alkali, preferably in the presence of an alcohol such as methanol or ethanol and heated at about 80° C. for two hours to saponify the partial esters by splitting off the polycarboxylic acid residue. By precipitation with mineral acids, the free 3-hydroxy-12-keto cholanic acid or its lower homologues can be isolated. These lower homologues as well as their esters are new compounds and represent valuable intermediates for the manufacture of valuable therapeutic products. Thus the 3-hydroxy-12-keto-*etio* cholanic acid ($x=0$ in the above formula) can be employed in the synthesis of certain naturally occurring hormones of the adrenal cortex.

These acids may, by treatment with acylating agents, be acylated in the 3-hydroxy group. By boiling for example with acetic anhydride, or by treatment of the pyridine solution with acetyl chloride or acetic anhydride, the 3-acetoxy 12-keto cholanic acid may be obtained in the usual way. In similar fashion the propionate, butyrate, benzoate and other 3-esters can be prepared.

The following examples set forth the invention in greater detail and by way of illustration:

35 EXAMPLE 1.—PREPARATION OF 3-HYDROXY 12-KETO CHOLANIC ACID

A. 3 (acid) succinate of desoxycholic acid

40 13 grams of succinic anhydride were dissolved in 50 cc. of anhydrous pyridine by warming. The solution was cooled to room temperature and 5 grams of desoxycholic acid were added. The reaction mixture was allowed to stand overnight and then poured into a mixture of 25 cc. H₂SO₄ and ice water. 5.7 grams of the succinate were obtained.

45 A small amount was recrystallized from dilute CH₃OH after treatment with charcoal for analysis.

$C_{28}H_{44}O_7$, M. Wt. 492, M. P. 231-232° C.: Calc., C 68.25; H 8.94%. Found C 67.98; H 8.79%. Saponification equivalent—

$$\frac{1000 \times .5 \text{ gram}}{.1 \times 30.98 \text{ cc.}} = \frac{161.4}{\times 3}$$

484.2 M. Wt. found
Calc. 492

Rotation $\alpha = +51.5$

B. Oxidation and saponification

5.7 grams of the succinate were dissolved in 125 cc. of acetic acid and an aqueous solution of 1.13 grams CrO_3 (1½ O) in 5 cc. water was added to the cold solution. The mixture was allowed to stand at room temperature for 5 hours and then poured into 1250 cc. of ice water and a little bisulfite. The mixture was chilled overnight and then filtered. The 3-acid succinyl 12-keto cholanic acid was saponified by heating on steam bath in aqueous alkali for 2-3 hours. The alkaline solution was filtered through supercel and the filtrate acidified with HCl.

4.7 grams of 3-hydroxy 12-keto cholanic acid, M. P. 163-164° C., were obtained. The material was then recrystallized from dilute CH_3OH , M. P. 164-65° C. (Wintersteiner M. P. 161-62° C.)

Rotation $\alpha = +86.6$

C. Oxidation using nitric acid

6.8 grams of the succinate were added slowly with stirring to a mixture of 55.5 cc. nitric acid (specific gravity 1.5) and 42 cc. acetic acid at a temperature of 5° C. The stirring and cooling were continued for 1½ hours and then the mixture was poured into ice water. The mixture was filtered and the 3-acid succinyl 12-keto cholanic acid was saponified by heating on steam bath in aqueous alkali for 2-3 hours. The alkaline solution was acidified with HCl. The 3-hydroxy 12-keto cholanic acid was recrystallized from dilute acetone.

5 grams M. P. 164-165°. Acetyl derivative M. P. 197-198° C. (Wintersteiner 197/8° C.)
Rotation $\alpha = 112.3$.

EXAMPLE 2.—PREPARATION OF 3-HYDROXY 12-KETO-NOR-CHOLANIC ACID

A. 3 (acid) succinate of nor-desoxycholic acid

5 grams of nor-desoxycholic acid, 13.0 grams of succinic anhydride and 50 cc. of anhydrous pyridine were allowed to stand overnight. The reaction mixture was then poured into 25 cc. H_2SO_4 and ice water and the succinate filtered and dried. The substance was recrystallized from ether plus petroether.

Yield—5.8 grams (90%). M. P. 241°-242° C.

Rotation $\alpha = +54.8$.

Analysis: $C_{27}H_{42}O_7$, calc., 67.74 C.; 8.84 H. Found, 67.54 C.; 9.06 H.

B. Oxidation and saponification

5.8 grams of the succinate were dissolved in 125 cc. acetic acid and an aqueous solution of 1.2 grams of CrO_3 (1½ O) was added to the cold acetic acid solution. The reaction was allowed to stand 5 hours at room temperature and then precipitated in ice and bisulfite. After chilling overnight and filtering, the precipitate was saponified in aqueous alkali.

4.8 grams of 3-hydroxy 12-keto-nor cholanic acid were obtained, M. P. 248-250° C. after recrystallization from dilute methanol.

Rotation $\alpha = +69.7$.

Analysis: $C_{23}H_{36}O_4$, M. Wt. 376; Calc. C 73.35%; H 9.65%. Found C 73.47%; H 9.70%. Acetyl derivative M. P. 207.8-209.5° C.

EXAMPLE 3.—PREPARATION OF 3-HYDROXY 12-KETO-BIS-NOR-CHOLANIC ACID

A. 3 (acid) succinate of bis-nor-desoxycholic acid

The succinate was made in the same way as for desoxycholic acid. The charge was 5 grams of bis-nor-desoxycholic acid, 12.5 grams of succinic anhydride and 50 cc. of anhydrous pyridine. The yield was 5.9 grams, M. P. 234-235° C. after recrystallization from ether plus petroether.

Rotation $\alpha = +33.9$.

Analysis: $C_{26}H_{46}O_7$, Calc. C 67.19; H 8.68. Found C 67.00; H 9.00.

B. Oxidation and saponification

This procedure is similar to the preparation of 3-hydroxy 12-keto cholanic acid, using 1½ O.

4.7 grams of 3-hydroxy 12-keto-bis-nor-cholanic acid were obtained, M. P. 283-288° C. The material was recrystallized from dilute CH_3OH and dilute acetone, M. P. 298-299° C.

Rotation $\alpha = +84.6$.

Analysis: $C_{22}H_{34}O_4$, Calc. C 72.86; H 9.46%. Found C 72.73; H 9.30.

Acetyl derivative M. P. 244-247.5° C.

EXAMPLE 4.—PREPARATION OF 3-HYDROXY 12-KETO ETIOCHOLANIC ACID

A. Succination

200 mg. of etio-desoxycholic acid were added to a cold solution of 525 mg. of succinic anhydride in 2.5 cc. of pyridine (anhydrous). The reaction was allowed to stand overnight at room temperature, heated for 1 hour on the steam bath and then poured into ice and H_2SO_4 . The mixture was extracted with ether and the ether extract dried and evaporated. M. P. 161-169° C.

40

200 mg. of etio-desoxycholic acid were added to a cold solution of 525 mg. of succinic anhydride in 2.5 cc. of pyridine (anhydrous). The reaction was allowed to stand overnight at room temperature, heated for 1 hour on the steam bath and then poured into ice and H_2SO_4 . The mixture was extracted with ether and the ether extract dried and evaporated. M. P. 161-169° C.

B. Oxidation and saponification

45 The 3 (acid) succinate of etio-desoxycholic acid was dissolved in 5 cc. acetic acid, cooled, and an aqueous solution of 57.5 mg. CrO_3 (1½ O) was added. After 5 hours at room temperature, the reaction was poured into ice water and bisulfite and chilled. The mixture was extracted with ether and the ether residue was saponified in aqueous alkali. 120 mg. of 3-hydroxy 12-keto etiocholanic acid were obtained, M. P. 210-212° C.

50 This material was dissolved in acetone and water added until turbid. The acetone was evaporated off under a funnel and the material crystallized in long needles. It was then recrystallized from acetone and ligroin. M. P. 213°-215° C.

Analysis: $C_{20}H_{36}O_4$, Calc. C 71.80%; H 9.04%.

60 Found C 71.60%; H 9.23%. α (dioxam) = +127.2. Acetyl derivative M. P. 205-206°.

While oxidation with chromic acid, with or without the addition of sulfuric acid, has proved to be highly satisfactory, other suitable oxidizing agents may be employed, for example, alkali permanganate in acetic acid solution or concentrated nitric acid.

Instead of the anhydrides of the acids employed to protect the 3-hydroxyl group there may, in certain instances, be employed the chlorides. In general, those polybasic acids may be used which form chlorides or simple anhydrides. In addition to the acylating agents disclosed hereinabove, there may be employed maleic and fumaric anhydrides.

I claim:

1. Succinic acid half-esters of a hydroxy keto-acid of the general formula

wherein Z is a radical of the group consisting of
—COOH,

and

2. The 3-acid succinate of 3-hydroxy-12-keto-
etio-cholanic acid.

3. Succinic acid half-esters of 3-hydroxy-12-
keto-
etio-cholanic acid.

4. 3-hydroxy-12-keto-
etio-cholanic acid.

5. 3-hydroxy-12-keto-bis-nor-cholanic acid.

6. Process for the manufacture of steroid keto
acids which comprises reacting a 3,12-dihydroxy
cholanic acid and a sufficient amount of a mem-
ber of the group consisting of the anhydrides and
chlorides of a polybasic organic acid to form the
3-partial ester, and thereafter oxidizing the sec-
ondary alcohol group in the 12-position to a keto
group.

7. Process according to claim 6 wherein the
acylating agent is succinic anhydride.

8. Process according to claim 6 wherein the
starting steroid acid is etio desoxycholic acid.

9. Process according to claim 6 wherein the
starting steroid acid is bis-nor-desoxycholic acid.

10. Process according to claim 6 wherein the
starting steroid acid is desoxycholic acid.

11. Process for the manufacture of 12-keto
steroid compounds, which comprises reacting a
3,12-dihydroxy steroid compound having in the
17-position a non-oxidizable group, with a mem-
ber of the group consisting of the anhydrides and
chlorides of a polybasic organic acid to form the
3-partial ester, and thereafter oxidizing the sec-
ondary alcohol group in the 12-position to a keto
group.

10 12. A steroid compound of the formula

20 wherein R is a succinyl radical.

13. Process for the manufacture of steroid keto
acids which comprises reacting a 3,12-dihydroxy
cholanic acid and a sufficient amount of a mem-
ber of the group consisting of the anhydrides and
chlorides of a polybasic organic acid to form the
3-partial ester, thereafter oxidizing the secondary
alcohol group in the 12-position to a keto group,
and saponifying the product to restore the 3-
hydroxyl group.

20 14. Process according to claim 13, wherein the
acylating agent is succinic anhydride.

15. Process according to claim 13, wherein the
starting steroid acid is etio-desoxycholic acid.
